UNITED STATES PATENT OFFICE.

BENJAMIN J. HAMILTON, OF HAVERHILL, MASSACHUSETTS, ASSIGNOR TO UNITED SHOE MACHINERY COMPANY, OF PATERSON, NEW JERSEY, A CORPORATION OF NEW JERSEY.

UPPER-STRETCHING MACHINE.

1,110,324.

Specification of Letters Patent.

Patented Sept. 15, 1914.

Application filed May 22, 1911, Serial No. 628,642. Renewed January 30, 1914. Serial No. 815,542.

To all whom it may concern:

Be it known that I, BENJAMIN J. HAMILTON, a citizen of the United States, residing at Haverhill, in the county of Essex and State of Massachusetts, have invented certain Improvements in Upper-Stretching Machines, of which the following description, in connection with the accompanying drawings, is a specification, like reference characters on the drawings indicating like parts in the several figures.

This invention relates to apparatus for preparing shoe uppers for lasting and particularly to means for treating the upper to cause it more readily and more completely to take the shape of the last in the lasting operation and more permanently to retain the original shape of the shoe while the shoe is being worn.

20 The portion of a shoe upper which demands the greatest degree of shaping in order to transform it from a flat piece of stock into the required shape as a portion of the shoe is the toe part of the vamp.

25 This part of the upper has to be convexed over the curved contour of the toe end of the last and then the fringe or margin has to be gathered inwardly over the edge of the last and secured on the last bottom. The

30 conspicuousness of this toe portion of the shoe makes it necessary that this portion of the upper be not only free from the wrinkles that naturally tend to form as the upper is thus bent and gathered in at its edge but for satisfactory appearance the stock must present an entirely smooth surface over the toe. This is a result which has been obtained with increasing difficulty as the old-fashioned square toes of shoes have gradually been changed to the modern shapes.

40 At the present time it has been rendered peculiarly difficult by reason of the "high toe" formation of a large portion of the lasts coming into use. These lasts have a much greater depth measurement through the toe than through the ball back of the toe and it requires a great deal of time and labor to manipulate the stock in the ordinary ways to cause it to fit smoothly over high toed lasts. This fact is recognized by the payment of an extra price for the lasting of shoes on high toed lasts.

45 It is one of the particular objects of this invention to meet this condition.

50 Another object is to obtain greater per-

manence of fit or contour in the shoe by removing the stretch from the stock more uniformly throughout the forepart of the vamp than is done by the usual methods. As will be readily understood an upper applied 60 loosely over a high toed last touches the last on the instep and on the top of the high toe and bridges between these points. In pulling-over and in lasting the shoe an attempt is made to draw the upper down to 65 the wood over which it is bridged and it proves very difficult to do this without tearing the upper or distorting it at the instep and the high toe. This difficulty is increased largely by the fact that in pulling 70 the upper the friction developed between it and the side face of the last in contact with which it is stretching absorbs a large part of the force applied. The result is that in most shoes the upper is overstretched over 75 the side faces of the ball and is not stretched enough over the top of the ball. When the shoe is put into use the portion of the upper over the ball stretches by the action of the foot and becomes loose and baggy, losing the 80 shape which it was intended the shoe should retain.

With these objects and others in view, the invention consists in providing means and mechanism such as pointed out in the annexed claims for treating a shoe upper preparatory to the lasting operation, or it might be as a part of the lasting operation considered in the broad sense in which the term lasting was originally used.

85 In the accompanying drawings is an illustrative example of a machine embodying the invention.

90 Figure 1 is a perspective view of the machine as seen at the beginning of the operation of stretching the upper. Fig. 2 is a vertical longitudinal section of the machine with its parts at rest in starting position. Fig. 3 is a front view with the parts positioned as in Fig. 2.

95 The machine is shown as having a post 2 with bearings for a main shaft turned by a pulley and belt 4 and connected by a sprocket chain 7 and two to one gearing to an upper shaft 8 driving a cam 10. The 100 main shaft is connected with the pulley 4 by a clutch which at each revolution is disconnected by a wedge controller 12 engaging a pin 13 to withdraw the clutch bolt. The pin comes to rest in a slot of the wedge con- 110

troller and thereby stops the shafts and determines the position in which the machine will come to rest. The controller is pivoted at 14 and a spring 15 connecting the lower 5 arm of the controller to a vertically inovable treadle bar 16 holds the controller normally in position to engage the pin on the clutch bolt. The bar 16 has on its upper end a shoulder 17 to 10 hook over an outwardly extending arm 18 of the controller whereby depression of the bar by a treadle, not shown, withdraws the controller to allow the clutch bolt to be crowded toward the pulley 4 by a spring not 15 shown. To insure only a momentary withdrawal of the controller and its return by the spring 15 to position to stop the machine, the controller has an arm 20 that abuts against the bar 16 when the controller 20 is rocked and thereby crowds the shoulder 17 off the arm 18.

The machine frame furnishes support for the upper holding devices which herein are shown as consisting of a clamp to engage a 25 vamp at the end of the toe and pairs of grippers to engage the vamp at each lateral edge back of the tip seam. The toe clamp consists of a fixed curved jaw 25 resting on the frame and a jaw 26 that is yieldingly 30 carried in a rising and falling head 30 operated by the cam 10 and guided in ways 32, Fig. 1. The jaw 26 has a pin and slot connection with the head at 34 and is pressed down by spring 35 so that it makes clamp- 35 ing engagement with the toe end of the vamp in the first portion of the descent of the head 30.

The side grippers are arranged in pairs and each gripper comprises a lower jaw 40, 40 Fig. 3, extending upwardly and forwardly from a slide bar 42 and having a gripping face on its upper side. The innermost position of this bar and jaw in the machine is adjustably determined for sizes of vamps 45 by a stop screw 43, Fig. 1. The bar 42 has upstanding ears to which is pivoted the upper jaw 45 which has a tail extending down through a hole in the bar 42 and through a fork in the end of an operating bar 46, said 50 fork being spanned by a roller carrying pin through which operating engagement is had between the jaw and bar 46 to swing the jaw down and up. The two operating bars 46 of the pair of side grippers are connected 55 together and to a block 48 by an equalizer 50, Fig. 1. The block 48 is arranged in the path of a lever 52 rising from a pivot rod 80 and having on its upper end a roll to engage with a wedge 55 that is carried by 60 the rising and falling head 30. This arrangement provides for seizing the vamp at the toe end and at two points at each edge of the ball when the head 30 descends and for causing the side grippers to stretch the 65 vamp transversely while it lies in a single

plane and there is no friction acting on its marginal portions to prevent thorough stretching throughout the width of the vamp. A yielding quality is given to this stretching by a spring 60 through which the action of the cam 10 is transmitted to the head 30. To adjust or vary the extent of the stretching movement of levers 52 the wedge 55 is made in two parts or members which can be spread by a right and left 70 screw 57. As was mentioned, the main shaft is connected to the upper shaft by two to one gearing so that the machine comes to rest with the upper gripped and under tension. 75

The frame gives support at 64 for a pan 65 located under the vamp to contain leather tempering liquid of any suitable composition. In this pan there is a brush 68 which is arranged to travel over a pair of toothed plates 70 located at each end of the brush and engaging therewith by pinions 72 affixed to the brush shaft at each end of the brush. The ends of the brush shaft are embraced by hooks 75 on the ends of arms 76 which are each formed in two parts to render the arms capable of extension against the resistance of springs 78. These arms extend from a rock shaft 80, which is the pivot shaft from which the levers 52 rise, and this shaft has an arm 82 that stands in the path of an arm 84 that is pivoted on a stud 31 that extends out from a depending leg of the rising and falling head 30. This arm 84 is held by a spring 86 in position to cause a steel plate 90 on its face to engage the arm 82 and turn the rockshaft 80 for causing the brush 68 to travel from one end of the pan to the other during the descent of the rising and falling head. The steel plate slips off the arm 82 before the head gets fully down, the arm 84 turning against the spring 86. The rock-shaft 80 has a third arm 90 connected to the plunger of a dash pot in which a spring 92 is compressed by the movement of the rock-shaft 80 during the described downward movement of the head 30. At the end of this downward movement of head 30 this spring 92 expands slowly, at a rate determined by the dash pot and causes the brush 68 to be 100 returned to its starting position. 105

The toothed plates 70 are also cam plates to determine the path of the brush, first upwardly from starting position Fig. 1, then across in wiping contact with the vamp, and then downwardly into the pan at the other end of the plates 70. This stroke of the brush quickly wets up the lining, if the vamp is placed lining side down. The return stroke of the brush effected by the spring 92 wets the work again while it is under tension. The bristles are long enough to allow bending to pass under the portions of the vamp that are depressed by the form that will be described, and their action on 110 115 120 125 130

the depressed portions applies the tempering liquid with particular force to those portions of the vamp while they are under tension. If it were desired to wet only those portions of the vamp which are particularly stretched by the form a brush of suitable diameter would effect this result. The brush is actuated from the head 30 so that it makes only one stroke across the vamp and back while the head 30 is descending and is down, and is not actuated when the head rises. The pan is kept supplied with tempering liquid at a uniform level by an air tight tank 93 and connections 94, and the liquid can be heated electrically or by a steam pipe 95.

The head 30 carries a form 96 that is shaped like the forepart of a last and which, after the upper has been seized and while it is held under tension and being further stretched by the action of the wedge 55 transmitted to the side grippers, is depressed upon the vamp and applies local pressure thereto at the high toe and at the base of the instep to stretch and shape the vamp of these points. The form is connected to the head 30 by stems 97 and a binding screw 98 which afford provision for adjustment to vary the extent to which the form shall be pressed into the vamp and caused to deflect it from the plane in which it is stretched by the holding devices 25, 26 and 40, 45. The machine comes to rest with the form down in shaping relation to the vamp. The form may be heated by an electrical or other heating device 99.

In the use of the machine the forepart of the vamp is inserted below the raised form and upon the horizontal gripping faces of the lower jaws 40 of the side grippers and upon the toe clamping jaw 25. The disposition of these jaws greatly facilitates the insertion of the work, as does also the open position of the pivoted gripper jaws whereby they are turned up entirely out of the way. Fig. 3 illustrates the work receiving position of the parts. When the machine is first treadled the rotation of cam 10 and depression of head 30 causes the jaw 26 to clamp the tip of the vamp, while the advance of wedge 55 causes the jaws 45 to grip the opposite lateral edges of the forepart of the vamp. Continued movement of the wedge effects movement of the grippers outwardly to stretch the vamp in a plurality of lines extending across the vamp and finally to come to rest with the work under tension at the end of one revolution of the driving shaft. The brush is actuated to wipe across the lower side of the upper materials of the vamp, that is, across the lining if there be a lining and the work be inserted with the finished side of the vamp uppermost as shown, (although a reverse presentation of the work is also contemplated

by me under some conditions) and to wet or to moisten the work on its lower side with the tempering liquid. This first wetting of the lining, which softens the starch and thereby reduces the resistance offered by the lining to the upper stretching action, is effected in accordance with the timed relation of actuating mechanism herein shown during the first portion of the stretching movement of the grippers. The return movement of the brush is delayed until after the machine comes to rest and takes place slowly under the control of the dashpot. The form 96 is positioned on head 30 to come into engagement with the vamp only after an initial stretching by the grippers has been effected without any retardation from frictional engagement of the stock with the form. The form then by pressure upon the vamp, first at the points over the toe and at the foot of the instep, bends the vamp out of the single plane in which the grippers are stretching it. The machine comes to rest with the form in pressing engagement with the upper and the latter held under tension and the brush, by reason of its long bristles, can adapt itself during its return stroke to the irregular surface presented by the contour of the form. It is to be noted that the vamp is first tensioned throughout its width while it can stretch freely and then it is further stretched locally by the action of the form at the points where the greatest displacement from normal position is required. If the form is heated, as herein provided, the heat penetrates the stock while the machine is at rest and assists the tempering liquid in softening the stock and causing it to set more perfectly in the shape of the form. The tempering liquid can be maintained at any desired temperature by the steam pipes. The heated form probably produces vapor to some extent from the moist lining. This apparatus has the advantage over some proposed toe steaming constructions that the finished surface of the leather is not necessarily moistened so that no injurious effects are obtained thereon, while the body portion of the leather can be quite thoroughly moistened by the warm vapor to render the stock pliable. Of course, the use of the heat, as well as also that of the form itself and of the moistening brush, is optional and the machine can be run simply as an upper stretching apparatus or with any one or more of the above mentioned features. When the machine is treadled a second time the parts are all restored to starting position as in Fig. 3 except the brush which was earlier returned by its spring 92. The raising of the head 30 and actuation of associated parts is effected by the lifting spring 100 that acts on the leg 31 of the head. It is contemplated that one operator

will be able to use two machines allowing a vamp to remain under tension and shaping pressure in one machine while another vamp is being placed in the other machine.

5 Although the machine has been described as for use in shaping a vamp wrong side out, it will be understood that the machine may be used to shape vamps right side out and that such use is within the province of the 10 invention. When the machine is used in the manner described, it will be understood that the vamp, after its removal from the machine, is to be turned right side out and subsequently lasted in the usual manner.

15 Having fully described my invention, what I claim as new and desire to secure by Letters Patent of the United States is:—

1. A machine for preparing upper materials for lasting having, in combination, 20 grippers arranged to engage the vamp at opposite edges of the forepart, means for actuating said grippers in opposite directions in the same horizontal plane to permit the vamp to be stretched in a single plane, and a 25 form between which and the vamp there is relative movement perpendicular to the direction of the stretching movement to shape the vamp.

2. A machine for preparing upper materials for lasting having, in combination, 30 a plurality of pairs of grippers arranged to engage the forepart of the vamp at opposite edges, an equalizer connected with the pairs of grippers at each edge, and means acting 35 through said equalizers for moving the grippers in the same horizontal plane to stretch the upper in a plurality of lines extending across the vamp from edge to edge.

3. A machine for preparing upper materials for lasting having, in combination, 40 two pairs of grippers engaging the forepart of the vamp at each edge, an equalizer connecting each two pairs of grippers, guiding means for directing the movement 45 of all the grippers in the same horizontal plane, levers acting through the equalizers to move the grippers, and a wedge for forcing the levers apart to effect the stretching of the upper.

50 4. A machine for preparing upper materials for lasting having, arranged for engagement with the forepart of a vamp at each lateral edge thereof, two pairs of grippers to stretch the upper in two lines extending transversely across the vamp, one 55 line being located adjacent to the tip seam and the other line being located adjacent to the throat of the vamp, an equalizer connecting the grippers that engage the same edge 60 of the vamp, and power actuating mechanism operating through said equalizers to effect stretching of the upper and arranged to come automatically to rest with the upper held under tension by the grippers.

65 5. A machine for preparing upper mate-

rials for lasting having, arranged for engagement with the forepart of the vamp at each lateral edge thereof, two pairs of grippers to stretch the upper in two lines extending transversely across the vamp, one 70 line being located adjacent to the tip seam and the other line being located adjacent to the throat of the vamp, an equalizer connecting the grippers that engage the same edge of the vamp, and operating means acting through said equalizers to cause the grippers to stretch the upper and hold it under tension. 75

6. A machine for stretching uppers having, in combination, grippers for engaging opposite edges of a vamp, levers connected with said grippers and having ends arranged in proximity, and a wedge adapted to be forced between said lever ends for effecting 80 operation of the grippers.

7. A machine for stretching uppers having, in combination, grippers for engaging opposite edges of a vamp, levers connected with said grippers and having ends arranged in proximity, and a split wedge 90 adapted to be forced between said lever ends for effecting operation of the grippers, said machine having provision for adjustment of the split wedge for varying the movement of the grippers. 95

8. A machine for stretching uppers having, in combination, grippers for engaging opposite edges of a vamp, levers connected with said grippers and having ends arranged in proximity, and a wedge arranged to be forced between said lever ends, a wedge carrier, a carrier operating cam, and a yielding element in the connection between the cam and the grippers. 100

9. A machine for stretching vamps arranged to receive the work with the vamp outspread in a single plane and having, in combination, a clamp for the toe end of the vamp, grippers for engaging opposite lateral edges of the vamp, means for actuating the grippers to stretch the vamp while the end is held clamped, a toe form and means for actuating it against the stretched vamp to shape it. 105

10. A machine for stretching vamps arranged to receive the work with the vamp outspread in a single plane and having, in combination, a clamp comprising jaws curved to correspond with the curvature of the toe tip, grippers arranged to engage the vamp back of the tip, means for actuating the clamp to seize the tip, and means for actuating the grippers to stretch the vamp back of the tip while the tip is so held. 110

11. A machine for preparing upper materials for lasting having, in combination, grippers arranged to seize opposite edges of the vamp and hold it outspread, means for actuating the grippers at opposite edges simultaneously to stretch the vamp, and means 115

- for applying tempering material to one face of the vamp while the grippers so hold the work.
12. An upper stretching machine having, in combination, means for stretching a vamp, means for moistening the vamp, and means for shaping the vamp after it has been moistened and while it is under tension.
13. A machine for preparing upper materials for lasting having, in combination, grippers arranged to seize opposite edges of the vamp and hold it outspread, a brush, and means for actuating the brush across the vamp while the grippers hold the work.
14. A machine for preparing upper materials for lasting having, in combination, grippers arranged to seize opposite edges of the vamp and hold it outspread, a brush, a pan for holding tempering liquid, and means for actuating the brush to take tempering liquid from the pan and apply it to the vamp while the work is held by the grippers.
15. A machine for preparing upper materials for lasting having, in combination, grippers arranged to seize opposite edges of the vamp and hold it outspread, a brush, a pan for holding tempering liquid, and actuating means to raise the brush into engagement with the vamp, move it over the vamp and lower it again into the liquid.
16. A machine for preparing upper materials for lasting having, in combination, grippers arranged to seize opposite edges of the vamp and hold it outspread, means for applying tempering material to the vamp, and actuating mechanism for operating the grippers and said means in timed relation.
17. A machine for preparing upper materials for lasting having, in combination, grippers arranged to seize opposite edges of the vamp and hold it outspread, means for applying tempering material to the vamp, and mechanism for operating said grippers and means in timed relation automatically to cause the grippers to stretch the upper and said means to apply the tempering material while the upper is under tension.
18. A machine for stretching shoe uppers having, in combination, means for gripping and stretching the vamp, and means operating automatically for moistening the shoe lining while the vamp is under tension.
19. A machine for stretching shoe uppers having, in combination, means for gripping and stretching the vamp, and connected mechanism for actuating the grippers to tension the upper and for applying stock softening material to the shoe.
20. A machine for preparing upper materials for lasting having, in combination, means for holding the forepart of the vamp in outspread condition, a brush located below the vamp, and means for actuating the brush across the vamp while it is so held.
21. A machine for preparing upper materials for lasting having, in combination, means for holding the forepart of the vamp in outspread condition, a brush located below the vamp, and connected mechanism for actuating the vamp holding means and the brush in timed relation and causing the brush to move across the vamp in contact therewith while the vamp is outspread.
22. A machine for preparing upper materials for lasting having, in combination, means for holding the forepart of the vamp in outspread condition, a pan, a brush arranged to receive liquid from the pan, and means for actuating the brush across the lower face of the vamp to apply the liquid to the shoe lining.
23. A machine for preparing upper materials for lasting having, in combination, means for holding the forepart of the vamp in outspread condition, a pan located below the vamp, a brush, means for actuating the brush, and guiding means for directing movement of the brush upwardly into contact with the vamp, across the vamp and returning it to position for receiving more liquid from the pan.
24. A machine for preparing upper materials for lasting having, in combination, means for holding the forepart of the vamp in outspread condition, a pan located below the vamp, a brush, and guiding and actuating means for raising the brush into contact with the vamp, moving it across the vamp, and down into the pan and for reversely moving the brush to starting position.
25. A machine for preparing upper materials for lasting having, in combination, means for holding the forepart of the vamp in outspread condition, a pan, a brush, and actuating means for causing the brush to move across the vamp and apply liquid thereto and then return in contact with the vamp, said machine having provision for retarding return movement.
26. A machine for preparing upper materials for lasting having, in combination, grippers for seizing opposite edges of the vamp and holding it under tension in a horizontal plane, a brush, means for supplying the brush with liquid, and actuating means for advancing the brush across the vamp in contact therewith to make an initial application of liquid to the work while the vamp is being stretched and for thereafter returning the brush more slowly across the work while the vamp is held under tension.
27. A machine for preparing upper materials for lasting having, in combination, grippers for seizing opposite edges of the vamp, means for actuating the grippers to stretch the vamp and hold it under tension in a horizontal plane, a brush, means for supplying the brush with liquid, means for actuating the brush across the vamp while

the vamp is being stretched, a spring for causing a return movement of the brush across the vamp while the vamp remains under tension, and a dash pot for insuring a relatively slow rate of return movement.

28. A machine for preparing upper materials for lasting having, in combination, means for holding a vamp in outspread position, a brush, means for supplying the brush with liquid, and means for actuating the brush a predetermined plural number of times across the vamp.

29. A machine for preparing upper materials for lasting having, in combination, means for holding a vamp in outspread position, a brush, means for supplying the brush with liquid, means for actuating the brush across the vamp, a spring for returning the brush across the vamp, and a dash pot for controlling the rate of return movement.

30. A machine for preparing upper materials for lasting having, in combination, grippers for engaging opposite edges of the forepart of a vamp, a form, and connected mechanism for actuating the grippers to stretch the vamp in a horizontal plane and for actuating the form into contact with the stretched vamp and forcing the vamp out of said plane at the points where stretching is required.

31. A machine for preparing upper materials for lasting having, in combination, grippers for engaging opposite edges of the forepart of a vamp, a form, means for actuating the grippers to stretch the vamp transversely out of contact with the form, and means for actuating the form into engagement with the stretched vamp to shape the vamp.

32. A machine for preparing upper materials for lasting having, in combination, means arranged to stretch the forepart of a vamp in a plane, a form, and means for thereafter bringing the form and the stretched vamp into engagement to shape the vamp in accordance with the contour of the form.

33. A machine for preparing upper materials for lasting having, in combination, means for initially stretching the forepart of a vamp transversely in a horizontal plane, a form, and operating mechanism maintaining the form out of frictional engagement with the vamp during the initial stretching of the vamp and causing the form to engage the vamp and further stretch it at certain points.

34. A machine for stretching uppers having, in combination, means for engaging the forepart of a vamp at its opposite edges, a form shaped like the forepart of a shoe, and operating mechanism for initially stretching the vamp out of contact with the form, then moving the form and the vamp relatively to

effect additional stretching and a shaping of the vamp over the toe and instep of the form and maintaining the vamp and the form in shaping engagement with the vamp under tension.

35. A machine for stretching uppers having, in combination, grippers for engaging opposite edges at the forepart of a vamp, a form, and mechanism operating in timed relation for causing the grippers to pull the upper for effecting stretching of the middle portion of the vamp while it is free from contact with the form and for thereafter moving the form into engagement with the tensioned vamp for further stretching the upper and shaping it to the form.

36. A machine for stretching uppers having, in combination, grippers for seizing an upper at opposite sides of the forepart of a vamp, a clamp for engaging the toe tip, means for actuating the grippers to stretch the upper transversely while the clamp holds the tip, a form, and means for moving the form into contact with the stretched upper while it is held by the grippers and the clamp.

37. A machine for stretching uppers having, in combination, grippers for seizing an upper at opposite sides of the forepart of a vamp, a clamp comprising curved edges for engaging and holding the curved edge of the toe tip, a form having high portions to shape the upper at the middle of the toe and at the base of the instep, means for actuating the grippers to tension the upper while the form is out of frictional engagement therewith, and means to actuate the form for further tensioning the upper at points corresponding in location to said high places.

38. A machine for stretching uppers having, in combination, a clamp to engage the toe of the vamp, grippers for engaging the opposite edges of the forepart of the vamp, a form for shaping the toe portion of the vamp, means for actuating the grippers to stretch the vamp while it is out of contact with the form, and means for relatively actuating the grippers and the form to cause the form to shape the toe portion of the vamp while it is under tension.

39. A machine for stretching uppers having, in combination, a clamp to engage the toe of the vamp, grippers for engaging the opposite edges of the forepart of the vamp, a form for shaping the toe portion of the vamp, and actuating mechanism to cause the grippers to stretch the vamp before the form is pressed into it, then to press the form into the vamp and come automatically to rest with the vamp under tension over the form, said mechanism being adapted thereafter to restore the parts to starting position and free the vamp.

40. A machine for stretching uppers having, in combination, upper holding devices,

- a toe shaping form, and operating mechanism for initially stretching the upper out of frictional contact with the form, then pressing the form into shaping engagement 5 with the upper and causing a rest in the machine's operation with the upper over the form, said machine having provision for raising the form and releasing the upper when it is restarted.
- 10 41. A machine for stretching uppers having, in combination, upper holding devices, a heated toe shaping form, operating mechanism for initially stretching the upper out of frictional contact with the form, then 15 pressing the form into shaping engagement with the upper and causing a rest in the machine's operation with the upper over the heated form, and means for maintaining the form in heated condition.
- 20 42. A machine for stretching uppers having, in combination, upper holding devices, a toe shaping form, means for moistening the upper materials, and operating mechanism for actuating said parts in timed relation and automatically causing a rest in the 25 machine's operation while the upper is held under tension in engagement with the form.
43. A machine for stretching uppers having, in combination, upper holding devices, 30 a heated toe shaping form, means for moistening the upper materials, operating mechanism for actuating said parts in timed relation and automatically causing a rest in the machine's operation while the moistened upper 35 is held under tension in engagement with the heated form, and means for maintaining the form in heated condition.
44. A machine for stretching uppers having, in combination, supporting mechanism 40 arranged to permit the presentation of a shoe vamp having a toe tip, grippers for seizing opposite lateral edges of the vamp back of the toe tip, means arranged for moistening the vamp back of the tip seam, and 45 connected means for actuating the grippers to stretch the engaged portion of the vamp relatively to the toe tip.
45. A machine for stretching uppers having, in combination, grippers for seizing opposite lateral edges of a vamp, means for moistening the vamp, means for actuating the grippers to stretch the vamp, and means for actuating the moistening means to moisten the vamp while it is being stretched.
- 55 46. A machine for stretching uppers having, in combination, grippers for seizing opposite lateral edges of a vamp, means for moistening the vamp, a form shaped like the toe portion of a shoe, and mechanism for actuating the grippers and the moistening means to stretch and moisten the vamp and for bringing the vamp and the form into 60 vamp shaping engagement.
- 65 47. A machine for stretching uppers having, in combination, grippers for seizing op-
- posite lateral edges of a vamp, means for moistening the vamp, a heated form shaped like the toe portion of a shoe, mechanism for actuating the grippers and the moistening means to stretch and moisten the vamp and 70 for bringing the vamp and the form into vamp shaping engagement, and means for maintaining the form in heated condition, said mechanism being constructed and arranged to come to rest with the heated form 75 in shaping engagement with the stretched vamp.
48. A machine for preparing upper materials for lasting having, in combination, means for seizing opposite edges of the fore-part of a vamp and stretching the vamp, and means for moistening the lining while the vamp is being stretched and again applying moisture to the vamp while it is held under tension.
49. A machine for preparing upper materials for lasting having, in combination, means for seizing opposite edges of the fore-part of a vamp and stretching the vamp, a brush, and actuating means for the brush 80 timed to cause the brush to apply moisture to the lining while the stretching movement is taking place and again while the vamp is held under tension.
50. A machine for preparing upper materials for lasting having, in combination, means for seizing opposite edges of the fore-part of a vamp and stretching the vamp, a form arranged to be brought into engagement with the vamp for shaping it, means 95 for applying moisture to the lining of the vamp, and automatic operating mechanism for said parts arranged to come to rest while the moistened materials are held under tension over the form.
51. A machine for preparing upper materials for lasting having, in combination, means for seizing opposite edges of the fore-part of a vamp and stretching the vamp in a horizontal plane, a form arranged for 100 movement to bend the vamp out of the horizontal plane for shaping the vamp, a brush, means for supplying the brush with liquid, and operating mechanism for said parts arranged to actuate the brush across the vamp 115 to wet the lining before engagement of the form with the vamp and to actuate the brush across the work again while the form is in vamp shaping position.
52. A machine for preparing upper materials for lasting having, in combination, means for engaging the vamp at opposite edges to subject the vamp to tension in a horizontal plane, a form movable into engagement with the vamp to subject it to 120 pressure perpendicular to said plane, and means operating automatically to apply moisture to the work while it is subjected to tension and again while it is subjected to pressure.

53. A machine for preparing upper materials for lasting having, in combination, means for subjecting the materials of the forepart of a vamp to tension, means for subjecting such materials to pressure, and mechanism for operating said means and for applying moisture to the vamp before it is subjected to pressure. 55
54. A machine for preparing upper materials for lasting having, in combination, 10 grippers arranged to engage opposite edges of the forepart of a vamp and to stretch the vamp in a horizontal plane, said grippers comprising supports, rigid jaws maintained by the supports with their gripping faces in said plane, pivoted jaws opening upwardly and outwardly and movable through 15 an angle of 90° to uncover the lower jaws and means for operating said jaws. 60
55. A machine for preparing upper materials for lasting having, in combination, a curved clamping jaw for the toe tip, a co-operating clamping jaw, and grippers for the lateral edges of the vamp comprising 20 lower jaws having their gripping faces in a horizontal plane with the toe clamping jaw and adapted to form therewith a support for the margin of the forepart of the vamp, and co-operating gripper jaws opening upwardly 25 and outwardly from the lower jaws through 30 an angle of 90° to uncover the lower jaws for the reception of the work. 65
56. An upper stretching machine having, in combination, means for stretching a vamp, 35 means for moistening the lining of the vamp, shaping means arranged to engage the leather of the tensioned vamp over the moistened lining, and means for heating the shaping means whereby heat is caused to 40 penetrate the upper leather and act on the moisture in the lining. 70
57. An apparatus for stretching vamps the linings of which are moist having, in combination, upper tensioning means, upper shaping means, shaper heating means, 45 and operating means therefor arranged to permit the heat from the shaper to penetrate the upper leather and act on the moisture in the lining while the vamp is under tension and shaping pressure. 75
58. An apparatus of the class described having, in combination, means for applying moisture in heated condition to the lining side of the shoe upper materials, means for 80 holding said materials in position to be treated, and connecting mechanism for operating said two means. 85
59. A machine of the class described having, in combination, means for holding the margin of the forepart of a vamp at the end and sides thereof, said holding means having provision for equalizing the strain between different holding points, a toe former, and means for relatively actuating said parts to force the former into the vamp for stretching the vamp in accordance with the shape of the former. 90
60. A machine of the class described having, in combination, means for holding the margin of the forepart of a vamp at the end and sides thereof, a toe former, means for relatively actuating said parts to force the former into the vamp for stretching the vamp in accordance with the shape of the former, said machine having provision for 95 allowing portions of the holding means to give up stock and other portions of the holding means to exert an increased pull as the vamp is being shaped by the former. 100
61. A machine of the class described having, in combination, means for holding the margin of the forepart of a vamp at the end and sides thereof, said holding means having provision for equalizing the strain between different holding points, a toe former, means for relatively actuating said parts to force the former into the vamp and maintain the vamp tensioned over the former, and means for heating the former. 105
62. A machine of the class described having, in combination, means for holding the margin of the forepart of a vamp at the end and sides thereof, a toe former and means for relatively actuating said parts to force the former into the vamp, said holding means including yielding grippers arranged to allow relative movement for permitting one portion of the stock to come toward the former relatively to another portion of the stock as the vamp is being shaped. 110

In testimony whereof I have signed my name to this specification in the presence of two subscribing witnesses.

BENJAMIN J. HAMILTON.
